US0D1096575S

(12) **United States Design Patent** (10) **Patent No.:** **US D1,096,575 S**
(45) **Date of Patent:** **** Oct. 7, 2025**

(54) **RIM**

(71) Applicant: **VOLVO CAR CORPORATION**, Gothenburg (SE)

(72) Inventor: **Alain Snoodijk**, Gothenburg (SE)

(73) Assignee: **VOLVO CAR CORPORATION**, Gothenburg (SE)

(**) Term: **15 Years**

(21) Appl. No.: **29/935,937**

(22) Filed: **Apr. 4, 2024**

(30) **Foreign Application Priority Data**

Oct. 5, 2023 (EM) 015036087-0006

(51) **LOC (15) Cl.** **12-16**

(52) **U.S. Cl.**

USPC **D12/211**

(58) **Field of Classification Search**

USPC D12/202, 204, 205, 206, 207, 208,
D12/209-213; D15/10, 33; D21/561,

(57) **CLAIM**

The ornamental design for a rim as shown and described.

DESCRIPTION

FIG. 1 is a front perspective view thereof;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a rear perspective view thereof.

The broken lines depict portions of the rim that form no part of the claimed design.

1 Claim, 8 Drawing Sheets
